TELEPHONE ENCLOSURE AND SUPPORT

Rowe L. Hartson, Galveston, Tex.

Application March 14, 1933, Serial No. 660,728

1 Claim. (Cl. 179—100)

This invention relates to telephone enclosures and supports and has for the primary object, the provision of a device which will effectively conceal and protect a telephone and aid in preserving the latter in a sanitary condition and providing the latter in a sanitary condition and providing an efficient support for writing purposes and accessories necessary thereto and support the receiver and transmitter of the telephone for use by a person so that the hands of the person may be free for writing and other uses.

With these and other objects in view this invention consists in certain novel features of construction, combination and arrangement of parts to be hereinafter more fully described and claimed.

For a complete understanding of my invention, reference is to be had to the following description and accompanying drawings, in which

Figure 1 is a perspective view illustrating an enclosure and support for a telephone constructed in accordance with my invention.

Figure 2 is a fragmentary transverse sectional view illustrating the same.

Figure 3 is a sectional view taken on the line 3—3 of Figure 2.

Figure 4 is a detail view illustrating a supporting bracket for a combined receiver and transmitter of a telephone.

Figure 5 is a sectional view taken on the line 5—5 of Figure 4.

Referring in detail to the drawings, the numeral 1 indicates a box or receptacle constructed from any material suitable for the purpose and may be of any artistic design other than that disclosed in the official drawings. The receptacle or box includes a bottom 2, side walls 3, a rear wall 4 and a front wall 5. The box or receptacle is closed by a cover 6, which when in an open position, provides an effective writing rest and is equipped with brackets 7 to support writing paper or a pad and clips 8 to support a pencil or like writing instrument.

The rear wall 4 is of a greater height than the front wall 5 and the side walls 3 are cut on an inclination, as clearly shown in Figure 1, and are adapted to support the cover when the latter is in a closed position. The bottom 2 is of a greater thickness than the remaining walls of the box or receptacle for the purpose of giving weight to the device to prevent accidental tipping or upsetting thereof and the bottom carries a pad 8 to prevent marring or scratching of the box or support on which the receptacle is positioned.

The telephone 9 is placed on the bottom 2 within the box or receptacle and is of the type com-

mercially known as the "French" phone wherein the receiver and transmitter are of a single unit, as shown at 10, normally resting upon the rack or circuit controller 11 of the telephone stand when in non-use. The telephone when positioned in the box or receptacle and with the cover closed will be protected from dirt and other foreign matter and further concealed from view and when it is desired to use the telephone or to remove the same from the box or receptacle, the cover 6 is swung into an open position, as shown in Figure 1. A spring catch 12 is provided for retaining the cover in closed position and is carried by the rear wall 4, the latter being removably mounted to the side walls by fitting in grooves formed in said side walls. The rear wall is provided with an opening 13 through which the electrical conductors of the telephone may pass.

A stand 14, consisting of telescopic sections adjustably connected by a set bolt 15, is removably secured to the base and the upper section has pivoted thereto an arm 16 having a bracket 17 connected thereto by a swivel joint of any suitable type to permit adjustment of the bracket relative to the stand or the arm 16. The bracket 17 consists of an elongated flanged body 18 having formed on its ends resilient gripping fingers 19 adapted to fit about the transmitter and the receiver of the unit 10, as shown in Figure 1. The fingers may be corrugated, as shown in Figure 3, to facilitate gripping of the fingers of the unit 10.

A person employing or using the telephone may place the unit 10 in the rack 17 so that the transmitter and receiver will be properly positioned to allow the person to hear and talk over the telephone, leaving the hands free for writing and other purposes.

The cover 6 is provided with a notch 20 to receive the stand 14 when the cover is in closed position.

While I have shown and described the preferred embodiment of my invention, it will be understood that minor changes in construction, combination and arrangement of parts may be made without departing from the spirit and scope of my invention, as claimed.

Having described the invention, I claim:

A device of the character set forth comprising a box having the upper edges thereof sloping from its rear wall towards its front wall and adapted to receive a telephone, a cover hinged to said box for closing the latter to conceal a telephone and forming a writing support when in an open position and located laterally to one side of the box, a vertical stand adjustable as to length mounted

to the bottom of said box and extending outwardly of the latter, said cover having a notch to receive the stand when positioned to close the box, an arm having a frictional and pivotal connection with the upper end of the stand and capable of being adjusted at various angles to the stand and towards and from the cover when occupying an open position, and a bracket secured

to the free end of the arm to removably receive and support a combined transmitter and receiver of the telephone and including an elongated flanged body provided with a plurality of resilient corrugated fingers at each end thereof to grip the telephone receiver and transmitter to retain the latter on the flanged body.
